UNITED STATES PATENT OFFICE.

SAMUEL SPITZER, OF NEW YORK, N. Y.

DESIGN FOR A PENDANT WATCH-BOW.

59,986.

Specification for Design.

Patented Dec. 13, 1921.

Application filed June 11, 1921. Serial No. 476,956. Term of patent 3½ years.

To all whom it may concern:

Be it known that I, SAMUEL SPITZER, a citizen of the United States, residing at New York city, borough of Manhattan, in the county and State of New York, have invented a new, original, and ornamental Design for a Pendant Watch-Bow, of which the following is a specification, reference

being had to the accompanying drawing, forming part thereof.

The figure is a face view of the pendant watch bow, showing my new design.

I claim:

The ornamental design for a pendant watch bow, as shown.

SAMUEL SPITZER.
